CLAIM

I claim the ornamental design for an belt, as shown and described.

DESCRIPTION

FIG. 1 is a perspective view of an belt showing my new design;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a back elevation view thereof; and,

FIG. 7 is a front elevation view thereof.

The broken lines depicting stitching represent portions of the belt that form no part of the claim.

The symbolic break lines depict the bounds of the claim. The area between the break lines forms no part of the claimed design.
